STABILIZED SOAP

Myers F. Gribbins, Wilmington, Del., assignor to
 E. I. du Pont de Nemours & Company, Wilming-
 ton, Del., a corporation of Delaware

No Drawing. Application March 19, 1945,
 Serial No. 583,637

14 Claims. (Cl. 260—398.5)

1

The present invention relates to stabilized soaps, to the manufacture of stabilized soap and soap products and especially stabilized soap and soap products made from ingredients, one or more of which ordinarily deteriorate or develop rancidity in a relatively short time and particularly to soap stabilization by substituted beta mercaptopropionic acid or its derivatives.

It is well known that soaps tend to become rancid and discolor after storage. It is not definitely known just what causes the deterioration but it has been suggested that it may be due to oxidation or chemical decomposition. Such deterioration is highly objectionable as it renders the soaps unattractive by blanketing in many instances the perfumes of the soap discoloring it and/or leaving an objectionable rancid odor on the skin or the article being cleaned. Many attempts have been made to overcome this deterioration, the addition of various substances having been proposed to inhibit or retard it.

An object of the present invention is to provide stabilized soaps. Another object is to provide compounds to be incorporated in the salts of fatty acids which will retard or inhibit their deterioration or prolong the period during which the salts are not rancid, which period is commonly referred to as the induction period, the salts so treated being free from the disadvantageous properties of compounds heretofore employed for this purpose. Still another object is to provide substituted beta mercaptopropionic acids and their esters as soap rancidity inhibitors. Other objects and advantages of the invention will appear hereinafter.

These objects may be accomplished in accordance with the invention by stabilizing liquid, jell-like and cake soap against rancidity by the incorporation therein of substituted beta mercaptopropionic acids or esters, by which is meant compounds containing the group

in which R is hydrogen, an alkyl, aryl, aralkyl or alicyclic group and in which the monovalent substituent "X" of the sulfur group is:

1. A hydrocarbon group such as e. g.: the alkyl groups: methyl, ethyl, propyl, butyl, lauryl, and the aryl groups: phenyl, naphthyl, benzyl; and such groups as p methoxy phenyl, p hydroxy phenyl and cyclohexyl, which gives respectively:

- a. 3-methyl mercaptopropionic acid
- b. 3-ethyl mercaptopropionic acid
- c. 3-propyl mercaptopropionic acid

2

- d. 3-butyl mercaptopropionic acid
- e. 3-lauryl mercaptopropionic acid
- f. 3-phenyl mercaptopropionic acid
- g. 3-benzyl mercaptopropionic acid
- h. 3-naphthyl mercaptopropionic acid
- i. 3-(p methoxy) phenyl mercaptopropionic acid
- j. 3-(p hydroxy) phenyl mercaptopropionic acid
- k. 3-cyclohexyl mercaptopropionic acid

10 Compounds of this type may be prepared by the addition of mercaptans to acrylonitrile followed by acid or alkaline hydrolysis of the nitrile group to produce the desired product.

15 Example.—3-ethylmercaptopropionic acid preparation

62 parts (1M) ethyl mercaptan is reacted with 53 parts (1M) acrylonitrile in the presence of 1 part piperidine (catalyst). This is an exothermic reaction and cooling is necessary. After 2 hours, the reaction mixture is distilled to isolate the addition product which distills at 94° C./11 mm. An 80% yield is obtained. Hydrolysis of the nitrile group is accomplished by heating the compound in an excess of concentrated HCl (Ca. 200 parts) for 1 hour. The by-product NH₄Cl precipitates out and is removed by filtration. Fractional distillation of the filtrate gives the desired product.

30 3-ethyl mercaptopropionic acid properties:
 Formula: CH₃CH₂—S—CH₂CH₂COOH.
 Molecular weight: 134.
 Boiling point: 93° C./2 mm.
 35 Neutral equivalent: 134.
 Solubility in water 20° C.: slightly soluble.
 Solubility in fats 20° C.: fairly soluble.
 Appearance: water white liquid.

40 2. An oxygenated-hydrocarbon group such, e. g., as: the alcohol groups: hydroxymethyl, hydroxyethyl, and hydroxybutyl; the ether groups: methoxymethyl, methoxyethyl, and ethoxyethyl; the acid groups: carboxymethyl, carboxyethyl, carboxypropyl and carboxybutyl; the aldehyde groups such as aldehydoethyl, which gives respectively:

- a. 3-hydroxymethyl mercaptopropionic acid

$$HOOCCH_2CH_2SCH_2OH$$
- 50 b. 3-hydroxyethyl mercaptopropionic acid

$$HOOCCH_2CH_2SCH_2CH_2OH$$
- c. 3-hydroxypropyl mercaptopropionic acid

$$HOOCCH_2CH_2SCH_2CH_2CH_2OH$$

- d. 3-methoxymethyl mercaptopropionic acid
 $\text{HOOCCH}_2\text{CH}_2\text{SCH}_2\text{OCH}_3$
- e. 3-methoxyethyl mercaptopropionic acid
 $\text{HOOCCH}_2\text{CH}_2\text{SCH}_2\text{CH}_2\text{OCH}_3$
- f. 3-ethoxyethyl mercaptopropionic acid
 $\text{HOOCCH}_2\text{CH}_2\text{SCH}_2\text{CH}_2\text{OC}_2\text{H}_5$
- g. 3-carboxymethyl mercaptopropionic acid
 $\text{HOOCCH}_2\text{CH}_2\text{SCH}_2\text{COOH}$
- h. 3-carboxyethyl mercaptopropionic acid (beta-beta thio-dipropionic acid)
 $\text{HOOCCH}_2\text{CH}_2\text{SCH}_2\text{CH}_2\text{COOH}$
- i. 3-carboxypropyl mercaptopropionic acid
 $\text{HOOCCH}_2\text{CH}_2\text{SCH}_2\text{CH}_2\text{CH}_2\text{COOH}$
- j. 3-carboxybutyl mercaptopropionic acid
 $\text{HOOCCH}_2\text{CH}_2\text{SCH}_2\text{CH}_2\text{CH}_2\text{COOH}$
- k. 3-aldehydoethyl mercaptopropionic acid
 $\text{HOOCCH}_2\text{CH}_2\text{SCH}_2\text{CH}_2\text{CHO}$

The type reaction is identical to that indicated in section 1. Specifically, oxygenated mercaptans are added to acrylonitrile and the nitrile group hydrolyzed by acid or alkaline treatment.

Example.—3 - hydroxyethyl mercaptopropionic acid preparation

27 parts (0.35M) mercapto glycol
 $(\text{HSCH}_2\text{CH}_2\text{OH})$

is added to 19 parts (0.35M) of acrylonitrile in the presence of 0.5 part piperidine. The reaction mixture is "topped" to remove unreacted materials and then heated in an excess of concentrated HCl (75 parts) for 1 hour. The by-product NH_4Cl precipitates out and is removed by filtration. Excess HCl and H_2O are removed by vacuum treatment. The product,

is a water white, thick liquid which decomposes on distillation. Neutral equivalent=150.

3. A sulfur-hydrocarbon group such, e. g., as: mercaptoethyl, mercaptopropyl, mercaptobutyl, mercaptoisobutyl, mercaptohexyl and ethiaethyl, which gives respectively:

- a. 3-mercptoethyl mercaptopropionic acid
 $\text{HOOCCH}_2\text{CH}_2\text{SCH}_2\text{CH}_2\text{SH}$
- b. 3-mercaptopropyl mercaptopropionic acid
 $\text{HOOCCH}_2\text{CH}_2\text{SCH}_2\text{CH}_2\text{CH}_2\text{SH}$
- c. 3-mercaptopbutyl mercaptopropionic acid
 $\text{HOOCCH}_2\text{CH}_2\text{SCH}_2\text{CH}_2\text{CH}_2\text{CH}_2\text{SH}$
- d. 3-mercptoisobutyl mercaptopropionic acid
 $\text{HOOCCH}_2\text{CH}_2\text{SCH}_2\text{CH}_2\text{CH}_2\text{CH}_2\text{SH}$
- e. 3-mercaptophexyl mercaptopropionic acid
 $\text{HOOCCH}_2\text{CH}_2\text{SC}_6\text{H}_{12}\text{SH}$
- f. Ethiaethyl mercaptopropionic acid
 $\text{HOOCCH}_2\text{CH}_2\text{SCH}_2\text{CH}_2\text{SC}_2\text{H}_5$

The type reaction is identical to that indicated in Section 1. Specifically, it involves the addition of molar amounts of dimercaptans to acrylonitrile, followed by acid or alkaline hydrolysis of the nitrile group.

Example.—6-mercapto - 4 - thiahexanoic acid preparation

To a solution of 329 parts (3.5M) ethanedithiol and 2 parts piperidine in 450 parts ethyl alcohol, 185.5 parts (3.5M) acrylonitrile is added dropwise over a period of 1 hour. Reaction temperature is maintained between 40-50° C. A precipitate of the di-addition product forms and is removed by filtration. Distillation of the filtrate gives the desired product $\text{HSCH}_2\text{CH}_2\text{SCH}_2\text{CH}_2\text{CN}$ boiling point 139-141° C./6 mm. in about 26% yield. Heating 20 parts of this nitrile in 75 parts concentrated HCl for 2 hours (in steam bath) produces the final product, a light yellow liquid, boiling point 142-143° C./2 mm. Neutral equivalent=166.

4. A sulfur- and oxygenated-hydrocarbon group such, e. g., as:

- 20 Carboxyethiaethyl,
 $-\text{CH}_2\text{CH}_2\text{SCH}_2\text{CH}_2\text{COOH}$
- Carboxyethiaethdithiaethyl,
 $-\text{CH}_2\text{CH}_2\text{SSCH}_2\text{CH}_2\text{SCH}_2\text{CH}_2\text{COOH}$
- Carboxyethiaisobutyl,
 $-\text{CH}_2\text{CH}_2\text{CH}(\text{CH}_3)\text{SCH}_2\text{CH}_2\text{COOH}$ and
- Carboxyethiaproplyl,
 $-\text{CH}_2\text{CH}_2\text{CH}_2\text{SCH}_2\text{CH}_2\text{COOH}$

which gives respectively:

- a. 4,7-dithiasebacic acid
 $\text{HOOCCH}_2\text{CH}_2\text{S}-\text{CH}_2\text{CH}_2\text{SCH}_2\text{CH}_2\text{COOH}$
- b. 4,7,8,11-tetrathiatetradecandoic acid
 $\text{HOOCCH}_2\text{CH}_2\text{S}-$
 $\text{CH}_2\text{CH}_2\text{SSCH}_2\text{CH}_2\text{SCH}_2\text{CH}_2\text{COOH}$
- 40 c. 5 methyl-4,8-dithiaundecandoic acid
 $\text{HOOCCH}_2\text{CH}_2\text{SCH}_2\text{CH}_2\text{CH}(\text{CH}_3)$
 $\text{SCH}_2\text{CH}_2\text{COOH}$

- d. 4,11-dithiatetradecanedioic acid
 $\text{HOOCCH}_2\text{CH}_2\text{S}(\text{CH}_2)_6\text{SCH}_2\text{CH}_2\text{COOH}$

Type reaction is identical to that indicated in Section 1. Specifically, it involves the addition of 2 moles acrylonitrile and 1 mole of a dimercaptan to give a sulfur containing dinitrile which can be hydrolyzed by acid or alkaline treatments.

Example.—4,7-dithiasebacic acid preparation

To a solution of 94 parts (1M) ethanedithiol and 1 part piperidine in 308 parts ethyl alcohol, 106 parts (2M) acrylonitrile is added dropwise over a period of 1 hour. Reaction temperature is maintained between 40-50° C. The dinitrile addition product $(\text{CH}_2\text{S}-\text{CH}_2\text{CH}_2\text{CN})_2$ precipitates out on cooling and is removed by filtration. It is easily recrystallized from hot 99% methanol. This dinitrile is reacted with 300 parts concentrated HCl for 1 hour (steam bath), during which the desired product, 4,7-dithiasebacic acid is formed and precipitates out.

4,7-dithiasebacic acid properties:

Formula:

- 70 Molecular weight: 236.
M. P.: 151° C.
Neutral equivalent: 118.
Solubility in water 20° C.: very slightly soluble.
Solubility in fat 20° C.: slightly soluble.
75 Appearance: odorless white crystals.

5. Or a sulfur-, nitrogen-hydrocarbon group such, e. g., as: 3-benzothiazyl mercaptopropionic acid

Example.—3-benzothiazyl mercaptopropionic acid preparation

To a solution of 167 parts (1M) mercaptobenzothiazol and 112 parts (2.0M) KOH in 600 parts dioxane at 50° C., 108 parts (1.0M) beta-chloropropionic acid is added dropwise over a period of 1-2 hours. The mixture is then heated at steam bath temperature for 2 hours, after which the dioxane is removed under reduced pressure. The thick slurry is then added to 600 parts water containing 2 moles HCl to precipitate the desired product and unreacted mercaptobenzothiazol. Twice recrystallization of this material from hot 99% methanol gives pure 3-benzothiazyl mercaptopropionic acid.

3-benzothiazyl mercaptopropionic acid properties:

Formula:

Molecular weight: 239.

M. P.: 149-150° C.

Neutral equivalent: 239.

Solubility in water 20° C.: slightly soluble.

Solubility in fats 20° C.: slightly soluble.

Appearance: white crystals.

These stabilizers may be incorporated in the soap in any suitable manner such, for example, as by simple mixing in proper proportions into the liquid or gel-like soap, by grinding, malaxing, or thoroughly and uniformly distributing it into the more or less solid soaps, the latter being subsequently formed into solid cakes or other shapes. Alternatively the stabilizers may be added at any convenient stage in the process of soap manufacture, care being exercised not to add it at a stage which will result in decomposition, leaching, or deterioration of the stabilizing agent. If desired, for example, these agents may be added during the well known crutching operation.

The stabilizers may be present in the soap to the extent of as little as 0.005%. The inhibiting powers of the particular agent used, or if a mixture is used, then the power of the mixture of agents will determine the exact amount that should be used for any desired duration of stabilization. The optimum amount to be used may be determined for any agent or mixture by preparing a series of compositions containing selected amounts for example from 0.005% to say 5% of the agent or mixture such as 0.001, 0.01, 0.1, 1.0, 2.5, and 5% or a more comprehensive series with smaller differentials if desired, placing these compositions under controlled storage conditions for the number of days the composition is to be maintained in the stabilized state. The composition that contains the minimum amount of stabilizing agent is the amount that should be used to stabilize the soap for the selected period. Amounts ranging from .01 to about 2% give excellent stability to the soap.

The stabilizers may be used in soaps generally for there are few if any that do not require some stabilization. The strong laundry soaps rancidify leaving undesirable odors. The delicate, more highly purified facial soaps likewise rancidify to destroy the perfume used. As example of the soaps that can be stabilized by these agents are included the alkali metal and alkaline earth metal as well as the heavy metal salts of the higher fatty acids and mixtures of salts of such acids and complex alcohols obtained by the saponification of the marine, vegetable, and animal oils and fats. The stabilizers are effective in water-soluble, water-insoluble and metallic soaps; the so-called mineral oil soaps, i. e., the water-soluble mineral oils and the like which are generally mixtures of mineral oils and oil soluble soaps which are used without water as a coolant in the machine tool industries and with water in the form of an emulsion as a coolant for cutting tools and as an insecticide spray; and in cosmetics compositions generally containing soaps which are used in tooth pastes, face and body creams, etc.

The surprising and unexpected stabilizing effect of the substituted beta mercaptopropionic acids and their derivatives is clearly demonstrated by the following tests. The test involves the examination of soap with and without the stabilizer for color, peroxide value and odor. The color is determined by visual examination; the peroxide value as included in the Swift test ("Oil and Soap" 10, 105-109, 1933), and the odor by placing aliquot portions of the soap with and without stabilizer in stoppered flasks of equal size, storing them under a constant temperature of about 50° C. At the end of each day, the stopper was removed and any odor indicating rancidity noted. The soap was combined with the stabilizer by malaxing the soap at about room temperature with the stabilizer. Table I tabulates the result of observations.

Table I

	Treatment	Days	Color	Peroxide value	Odor
A		1	White	1.8	None.
B		1	do	2.4	Do.
A		4	Brown	9.2	Rancid.
B		4	White	2.8	None.
A		10	Brown	21.0	Rancid.
B		10	Buff	2.8	Slightly rancid.

A. Soap with no stabilizer.

B. Soap with 1% thiadipropionic acid.

The stabilizers described under the 5 groups and their equivalents may be used as the acid, ester or salt. Generally as specific examples of the esters may be included the methyl, ethyl N- and iso-propyl, N- and iso-butyl and the higher straight and branched chain alkyl esters as well as the alicyclic ester cyclohexyl. As specific examples of the salts are included the alkali metal and alkaline earth metal salts and particularly the sodium, potassium, calcium and magnesium salts.

I claim:

1. A process which comprises protecting soap against rancidity by incorporating therein a compound selected from the group consisting of 3-hydrocarbon substituted mercaptopropionic acids, their esters and salts.

2. A process which comprises protecting soap against rancidity by incorporating therein a compound selected from the group consisting of

3-oxygenated hydrocarbon substituted mercapto-propionic acids, their esters and salts.

3. A process which comprises protecting soap against rancidity by incorporating therein a compound selected from the group consisting of 3-sulfur hydrocarbon substituted mercapto-propionic acids, their esters and salts.

4. A process which comprises protecting soap against rancidity by incorporating therein a compound selected from the group consisting of 3-sulfur- and oxygenated-hydrocarbon substituted mercapto-propionic acids, their esters and salts.

5. Soap stabilized against rancidity by a compound selected from the group consisting of 3-hydrocarbon substituted mercapto-propionic acids, their esters and salts.

6. Soap stabilized against rancidity by a compound selected from the group consisting of 3-oxygenated hydrocarbon substituted mercapto-propionic acids, their esters and salts.

7. Soap stabilized against rancidity by a compound selected from the group consisting of 3-sulfur-hydrocarbon substituted mercapto-propionic acids, their esters and salts.

8. Soap stabilized against rancidity by a compound selected from the group consisting of 3-sulfur- and oxygenated-hydrocarbon substituted mercapto-propionic acids, their esters, and salts.

9. A soap comprising a water soluble salt of a higher fatty acid stabilized against deterioration and development of rancidity by having incor-

porated therein more than 0.005% of a compound selected from the group consisting of 3-hydrocarbon substituted mercapto-propionic acids, their esters and salts.

10. A soap comprising a water soluble salt of a higher fatty acid stabilized against deterioration and development of rancidity by having incorporated therein more than 0.005% of a 3-carboxyethyl mercapto-propionic acid.

11. Soap containing 1% by weight of 3-carboxyethyl mercapto-propionic acid.

12. Soap stabilized against deterioration and development of rancidity by having incorporated therein more than 0.005% of a 3-carboxyethyl mercapto-propionic acid salt.

13. Soap stabilized against deterioration and development of rancidity by having incorporated therein more than 0.005% of a sodium salt of 3-carboxyethyl mercapto-propionic acid.

14. Soap stabilized against deterioration and development of rancidity by having incorporated therein more than 0.005% of 3-benzyl mercapto-propionic acid.
